**FASTENER DRIVING INTERLOCKING
 PISTOL OR TOOL**

Pierre Termet, 16 Impasse Belloeuf, Lyon 3, France
 Filed Nov. 24, 1958, Ser. No. 775,951
 Claims priority, application France Nov. 29, 1957
 3 Claims. (Cl. 1—44.5)

The present invention relates to improvements in fastener driving tools adapted to drive fasteners, studs or the like workpiece materials.

The present invention is particularly concerned with improvements applicable to fastener driving pistols or tools, wherein the gases produced by the explosion of an explosive cartridge cause an intermediate piston to be propelled and strike the fastener or stud contained in the pistol to drive the former into the workpiece in the same manner that a nail is driven by a hammer stroke.

In the devices known up to the present day, whether of this or any other type, it was indispensable to use cartridges having different explosive powers, selected on the one hand as a function of the hardness of the material into which one desired to drive the fastener or stud, and on the other hand according to the desired fastener penetration depth.

According to the present invention, there has been provided a power adjustment or control device whereby it is possible to use a standard explosive cartridge having a predetermined explosive power, and the adjustment or control of said device permits the regulation of the force acting on said fastener or stud according to the material into which it is to be driven.

Such power adjustment or control device according to the present invention is essentially characterized by the fact that the pistol firing chamber containing a loaded cartridge is closed by a rod integral with the piston driving the fastener into the material. As soon as the explosion occurs, the rod integral with the piston moves and uncovers a variable cross-section orifice through which a portion of the gases resulting from the cartridge explosion may be evacuated to the outside surrounding atmosphere.

Said power adjustment or control is obtained on the one hand by varying the cross-sectional area of the orifice through which gases are allowed to escape outside, and on the other hand by varying the firing chamber volume prior to firing the cartridge.

According to the present invention, gas escapes outside the pistol, thus permitting the control of the power thereof as it flows between the cartridge holder and a cylinder element in which the piston moves, said cylinder element being displaceable in an axial direction with respect to the cartridge holder by means of a threading.

It is an object of this invention to provide a device adapted for holding said fastener, stud or the like in a fixed position within the pistol barrel, said device being essentially characterized by having a plurality of magnets arranged in a longitudinal direction around said barrel and contained in a support member made from a non-magnetic material.

It is another object of this invention to provide a device adapted to maintain at the pistol barrel muzzle end attachment members intended to be fixed in the workpiece material by means of a fastener, stud or the like, said device being essentially characterized by the fact that it comprises at the pistol barrel muzzle end a recess the shape of which mates with that of said attachment member intended to be fixed, and said recess having at the bottom thereof one or more magnets adapted to maintain said attachment members in a fixed position.

In order that the present invention may be more fully understood and carried into practice, the same will be

2

now described in an illustrative and by no means limitative manner of the scope of this invention as claimed in the appended claims, and with reference to the annexed drawings, in which:

5 FIG. 1 is an elevation view in longitudinal section of a fastener driving interlocking pistol or tool according to the present invention.

10 FIG. 2 is an enlarged fragmentary view corresponding to FIG. 1, with the pistol open so that the cartridge may be loaded therein.

FIG. 3 is an enlarged fragmentary view showing how the adjustment or control of the power may be effected.

15 FIG. 4 is a view corresponding to FIG. 3 of a modified form of the device according to this invention.

FIG. 5 is a fragmentary sectional view showing a modified form of the ejection means according to the present invention.

20 FIG. 6 is a perspective view showing an attachment member at the barrel muzzle end.

FIG. 7 is a sectional view taken along VII—VII in FIG. 1; and

25 FIG. 8 is a perspective view showing the arrangement of the magnets around the pistol barrel.

Referring to the drawings, there is shown a cartridge holder 1 on which a breech 2 is screwed by means of an externally threaded part 3.

30 A guiding cylinder 4 adapted to guide a piston 5 is held in an adjustably fixed position by means of threads 6 in a sleeve 7, which is in turn, screwed on the cartridge holder 1.

35 There is provided a knurled internally threaded ring 10 adapted to lock the cylinder 4 relatively to the sleeve 7. Said ring 10 bears an adjusting mark 11 which cooperates with a scale 12 on the cylinder 4, to permit accurate adjustment of the position of the cylinder 4 relatively to the sleeve 7.

An internally threaded end part 13 of the cylinder 4 supports a tube 14 which acts as a guide for the fastener or stud when firing occurs. Said tube 14 is extended inwardly of the pistol by a cage 15 provided with a cap 16 made from nonmagnetic material and containing magnets 17.

40 The tube 14 comprises also hollow screws 18 containing magnets 19, the right hand ends of which (viewing FIG. 1) are flush with the bottom of a recess 20 provided at the pistol barrel muzzle end for a purpose discussed later.

The barrel muzzle end of the pistol or firing tool is also provided with a flash shield 21 as a protection against possible ricochets and spalling of the workpiece material, said shield being made from a plastic material such as Rilsan. A tubular casing or socket 22, screwed on the breech 2 at 23, is slidably mounted over the sleeve 7, thus guiding the front part of the pistol when opening the breech, as shown in FIG. 2.

45 Said socket 22 is provided with orifices 24 and 25 through which, when open, a new cartridge may be loaded and the spent cartridge case removed.

An outer casing 26 fixed to sleeve 7 surrounds the 50 socket 22 and covers the orifices 24 and 25, and limits the movement of the front part of the pistol by means of its shoulder 27 which engages a shoulder 28 provided at the front end (viewing FIG. 2) of tubular element 22.

The breech is provided with a striker or firing pin 29 which is thrust forwardly under the action of a firing pin spring 30.

55 In order to fire the pistol, said firing pin 29 is released by a trigger 31, which moves a detent or locking element 32 against the action of detent return spring 33.

60 Owing to safety reasons, the pistol or tool organization is such that it is necessary (1) to make use of a manual force on a hand grip 34 in the direction of arrow 35, so

that the trigger 31 may act upon the detent 32, and (2) to make use of a manual force on a lever 37 to release a stub or pawl 38 which would otherwise butt against the rear or left end (viewing FIG. 1) of the breech 2.

Thus, when these two conditions are effected (i.e. the movement of the hand grip 34 in the direction of arrow 35, and the manual pressure in the direction of arrow 36 on the lever 37 to release the stub 38), said trigger is in a condition to release the firing pin 29 and thus to fire the pistol cartridge.

The drawings show clearly how the part integral with the hand grip 34 slides on the breech 2.

A stub 39, which is integral with the hand grip 34, moves in a groove 40 cut in the rear part of the breech 2 and constrains the latter against any relative movement of rotation with respect to the hand grip 34.

The cartridge holder 1 is provided with a pair of holes 41 in which are slidably mounted ejector pins 42 urged leftward or backward by ejector pin springs 43.

Screws 44 are provided respectively not only to limit the travel of the extractor pin 42 but also to lock the same against any rotation.

In the pistol or tool form illustrated in FIG. 5, the cartridge extraction is merely effected by means of a small plate 45 screwed on the breech 2 inside the same, and below which is engaged the outside periphery of a cartridge 46, as seen in FIG. 5.

Thus, it can be understood that upon opening of the breech 2, said cartridge 46 is withdrawn from the bore thereof.

FIGS. 3 and 4 show at an enlarged scale how is effected the power adjustment or control according to the present invention.

In the form shown in FIG. 3, the piston 5 which slides within the cylinder 4 is extended at the rear thereof (viewing FIG. 3) by a cylindrical rod 47, the free tapered end 48 of which terminates in a concave cup-shaped recess 49.

The distance between the piston 5 and the end 49 of the rod 47 is such that, regardless of the position of the cylinder 4 with respect to the breech holder, said end 49 of rod 47 bears on a shoulder 50 cut in the cartridge holder 1.

It should be particularly noted that the tapered end 48 of the rod 47 shows substantially the same tapering as does the breech-holder corresponding part, but that said two tapered parts do not engage one with the other so as to avoid any jamming.

There has been shown in solid lines the position of guiding cylinder 4 corresponding to the lowest power of the device (i.e. to the adjustment used to drive studs or the like into relatively soft materials), while the position of said guiding cylinder 4 is shown in phantom lines in the case of a maximum power adjustment (i.e. to drive studs or the like into hard materials).

It is to be understood that the section of the free space between the end 52 of cylinder 4 and the corresponding part of the cartridge holder 1 varies as said cylinder is moved between its two extreme positions.

There can be seen that, upon firing of the cartridge 46, the firing chamber is in the form of a closed space (owing to the engagement of the free end 48 of the rod 47 with the shoulder 50), but as soon as the piston unit 5 has begun to be propelled forwardly under the action of the powder combustion gases, these gases can partly escape between the end 52 of the cylinder 4 and the breech holder in a path as shown by the arrows in FIG. 3, such gas escape being consistent over the whole inside periphery of the guiding cylinder 4 and said gases being at last discharged to the surrounding atmosphere through baffles 53 (FIG. 1) which avoid excessive noise.

The non evacuated gas part causes the piston unit 5 to be propelled forwardly within cylinder 4, a piston sealing ring 54 being provided in a circular groove cut in said piston to avoid gas leakage.

When the piston 5 passes beyond an orifice or hole 55 drilled in cylinder 4, the gases which propelled said pis-

ton are then led outside to the atmosphere through the baffles 53.

A rubber tubular element 56, which is used as a brake for the piston, is driven to engage a washer 57 made from a resilient plastic material such as, e.g. polyvinyl chloride.

According to the present invention, said washer 57 is disposed between the rubber tubular element 56 acting as a buffer or shock-absorber and the pistol tube 14, thus avoiding a premature wearing of the buffer 56.

When the piston unit 5 is propelled forwardly under the firing action, a rod 58 which is integral therewith drives the fastener or stud into the workpiece material.

It can be seen that the effective space left available for gas flow between the guiding cylinder 4 and the cartridge holder 1 determines on the one hand the amount of gases acting effectively on the piston 5 and used to drive in the stud, and on the other hand the amount of gases led directly to the outside atmosphere.

In the second form of the fastener driving pistol according to this invention shown in FIG. 4, the tapered end 48 of rod 47 is provided with a cylindrical extension 48a extending into the firing chamber 51.

In said pistol form, the piston 5 bears, before firing, against the bottom of cylinder 4 which acts as a guide for the piston, but said tapered portion 48 of rod 47 never moves to engage the corresponding tapered portion of the cartridge holder, thereby avoiding any jamming thereof.

There is shown in solid lines in FIGURE 4 the cylinder and piston positions corresponding to the minimum power, and in phantom lines the pistol adjustment corresponding to the maximum power.

In this pistol form, it can be seen, upon firing a cartridge, that the firing chamber comprises a closed space which opens to the outside after a small movement of the piston 5.

In the structure corresponding to FIG. 4, the initial firing chamber volume varies as a function of said adjustment, owing to the fact that, prior to firing, the piston 5 bears always on the bottom of cylinder 4. Consequently, when said adjustment is made to correspond to a low power, the firing chamber comprises at the moment of firing a greater volume compared to the volume that said chamber comprises when the adjustment is made to correspond to the maximum power.

Now, it is well known that the lower the firing chamber volume the higher the power of a cartridge.

It can be seen easily that in this second pistol form according to the present invention, power adjustment is effected by two effects, namely (1) varying the initial firing chamber volume, and (2) varying the cross-section area available for gases flowing directly to the surrounding atmosphere.

Thus, with the fastener driving pistol or tool according to the present invention it is possible by using a cartridge having a predetermined power to drive all the types of fasteners, studs or the like into the most different materials, which necessitated hitherto using a wide range of cartridges.

According to this invention, the fastener or stud 59 is held in a fixed position before firing by means of the aforementioned magnets 17 arranged around the inside of the tube 14 in a housing or recess made from a non magnetic metal.

Said magnet organization is shown in FIGS. 7 and 8. There can be seen in the sectional view in FIG. 7 the aforementioned cage 15 and the pair of cylindrical magnets 17 housed within bores drilled in the cage.

FIG. 8 shows said magnets 17 held by means of the recited cap 16 within bores 17a drilled in said cage 15.

With such an organization, the magnets engage directly the fastener or stud and insure effectively the holding thereof.

On the other hand, said magnets have a sufficient clearance to freely pass the rod 58 integral with piston 5 which propels forwardly the stud 59 upon firing of the pistol.

According to the present invention, there is provided also a pair of magnets 19 at the bottom of the housing or recess located at the barrel muzzle end, said magnets being contained within hollow screws 18 maintaining the attachment member 60 which is to be fixed to the work-piece by means of the fastener or stud.

In FIG. 6 there is shown in perspective the barrel muzzle end without the flash shield 21. It can be seen in this figure how the attachment member 60 is held by the magnets in the corresponding recess 20 and may be thus in a fixed position when the fastener or stud is propelled upon firing the pistol cartridge.

It is to be understood that many modifications and arrangements of parts may be designed by those skilled in the art without departing from the scope of this invention as illustrated and defined in the appended claims.

What I claim is:

1. An explosion-actuated fastener-driving tool having a barrel for receiving a fastener to be driven, a breech block defining a firing chamber, cylindrical means defining a piston chamber between said barrel and firing chamber, and piston means slidably in said piston chamber between a rear position in which said piston means closes one end of said firing chamber and a forward position axially removed therefrom, said cylindrical means comprising a transverse wall portion mounted for axial adjustment relative to said breech block, said adjustable wall portion constituting a rear wall for said piston chamber through which one end of said piston means projects and defining with the forward part of the firing chamber wall an adjustable vent by-passing said piston chamber through which the forward end of said firing chamber is connected to the exterior of the tool, said vent being blocked by said piston means when it closes said firing chamber but progressively opened by said piston means as it moves forward. 35

2. A tool as claimed in claim 1 comprising also means for locking said adjustable wall portion in any of a plurality of positions relative to said breech block.

3. A tool as claimed in claim 1 in which said firing chamber opens at its forward end into an axial bore which tapers inwardly toward said firing chamber, and the rear surface of said adjustable wall portion is tapered to project into said bore, the rearward end of said piston means being less sharply tapered than at least part of said bore and extending completely therethrough to close the forward end of said firing chamber when said piston is in its rear position.
